CLAIM

The ornamental design for a bundle package for noodles, as shown and described.

DESCRIPTION

The file of this patent contains at least one drawing executed in color. Copies of this patent with color drawing(s) will be provided by the Patent and Trademark Office upon request and payment of the necessary fee.

FIG. 1 is a color photograph showing the front of a bundle package for noodles according to my new design.

FIG. 2 is a color photograph showing a perspective view, taken slightly from above, of the front and left sides of the bundle package for noodles according to my new design; FIG. 3 is a color photograph of the left side of the bundle package for noodles according to my new design;

FIG. 4 is a color photograph of the bottom of the bundle package for noodles according to my new design;

FIG. 5 is a color photograph of the top of the bundle package for noodles according to my new design;

FIG. 6 is a color photograph of the rear of the bundle package for noodles according to my new design; and,

FIG. 7 is a color photograph of the right side of the bundle package for noodles according to my new design.
